UNITED STATES PATENT OFFICE

DAVID D. GORDON, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PLUG.

1,236,161.

Specification of Letters Patent.

Patented Aug. 7, 1917.

Application filed March 6, 1916. Serial No. 82,339.

To all whom it may concern:

Be it known that I, DAVID D. GORDON, a citizen of the United States, residing at Chicago, in the county of Cook and State 5 of Illinois, have invented a certain new and useful Improvement in Plugs, of which the following is a full, clear, concise, and exact description, reference being had to the accompanying drawings, forming a part of 10 this specification.

My invention relates to attachment plugs and more particularly to that style of attachment plug known as a separable attachment plug. My invention more particularly 15 is an improvement over my application Serial No. 82,338, filed March 6, 1916.

My invention further has for its object the provision of a separable attachment plug of this nature which at the same time may 20 be of the swivel type. In general, my plug consists of what might be called two body members which are separable, one of the body members having means whereby it may be held in the socket and having a conducting 25 portion forming part of the electrical connections for one side of the circuit, the other body member having means for connecting with this said conducting portion, and having at the same time a further conducting portion adapted directly to engage 30 one of the socket terminals.

In one form of the device as above set forth, these two body members when they are in contact making position in the socket, 35 and also when removed therefrom, are adapted for relative rotation, thus making them of the swivel type.

I will explain specifically two forms of carrying out these two ideas more in detail 40 by referring to the accompanying drawings, in which—

Figure 1 is a sectional view of a socket having mounted therein a plug constructed in accordance with my invention;

Fig. 2 is an end view of one of the body members of the socket;

Fig. 3 is an end view similar to Fig. 2 showing a modified form of the body member structure;

Fig. 4 is a sectional view on line a—a of Fig. 3;

Fig. 5 is a side view of the plug shown in Fig. 1;

Fig. 6 is a sectional view of a modified 55 form of plug;

Fig. 7 is a detail of construction, and Fig. 8 is an end view of the member 6 showing the construction of the members through which electrical connection is made.

Referring more particularly to Fig. 1, I 60 show a socket 1 having the central contact 2 and the outer or screw threaded contact 3. This socket is adapted to accommodate my improved plug 4, which plug has the body members 5 and 6. These body members are 65 separable. The body member 5 is provided with a screw threaded periphery throughout a portion of its length as shown at 7 so that it may be held in the socket. The said body member also is provided with a plurality of 70 grooves 8 adapted to accommodate a conducting spring 9, which conducting spring 9 is mounted upon the body member 6. The grooves 8 continue through the finger piece 10, preferably as holes 11 through which 75 the spring 9 may be inserted in position. The spring 9, as shown, has a shoulder at 12 by which the two body members are normally locked together when they are in the position shown in Fig. 1. The contact 80 spring 9, as shown, is adapted to directly engage the outer screw threaded portion of the socket, there being no conducting portions for that particular side of the circuit provided upon the body member 5. The 85 body member 5 has preferably, although not necessarily, a conducting portion 13 which is adapted to receive the conducting element 14 which is mounted upon the body member 6. This conducting portion 14 is inserted through the central opening 15 of the body member 5 and then is normally adapted to make electrical contact with the element 13. It may be desired, however, to omit any conducting portion upon the body 90 5, in which event the conducting rod 14 may directly engage the central contact 2 of the socket. In that event I should prefer to use the construction shown in Fig. 7 where the conducting rod 14^a is provided with a 95 resilient extremity 15, which is normally pushed outwardly by the spring 16, being prevented from relative displacement from the rod 14^a by the pin 17 operating in the grooves 18. Thus a good contact would be 100 assured for the center connection, the spring 9 holding the plug portions together as stated, or other suitable grasping means provided to hold the body portions yielding together. The body portion 5 is 105 110

dished as shown at 19 so as to permit ready insertion of the rod 14. A plurality of holes 11 are provided so that only forty-five degrees, for instance, would be required to turn the body portion 6 when inserting said body portion in position.

It will be noticed that the structure is to this extent practically symmetrical as more than one spring 9 could be employed to 10 make it symmetrical, if so desired, although one is for practical purposes sufficient at the present time. There is thus a practically symmetrical arrangement and no difficulty would be experienced by the inexperienced 15 operator in attaching the two portions of the plug together.

In Figs. 3 and 4, it will be more clearly seen that in this modified form the space between the holes 11 is constructed on the 20 hill and valley order so that a guide is afforded the conducting spring 9 toward any hole whenever connection is attempted.

In Fig. 6 I show a modified form of plug in which I am enabled to produce a plug 25 which is not only of the separable type, but which is also of the swivel type, in that the body member 6^a may swivel relatively to the body member 5^a both whenever the plug is in the socket or when it is out of the 30 socket. The construction may of course be such that the body member 5^a carries contacts or does not carry contacts as may be desired. By thus swiveling the two elements of the plug the advantages of having 35 the cord remain untangled are obtained. The body member 5^a may then merely serve as a sort of guide to properly direct the conducting portions of the body member 6^a and serving at the same time as a base about 40 which the body member 6^a may swivel. In the particular form shown the body member 5^a has spring clips 20 to more thoroughly hold the head 21 of the rod 14. As before stated, this rod 14 may again be replaced 45 by such a structure as shown in Fig. 7, in which case a spring 20 may be absent, for conducting purposes, or may serve merely as clasps to yieldingly hold the body members together, although in this particular 50 structure other means are shown for performing this function in the shape of the springs 9^a. The rod 14 is again secured to the body portion 6^a and the spring 9^a is also secured to said body portion 6^a. The body 55 member 5 has a groove 21^a which is adapted to coöperate with the bent portion 22 of the spring 9^a to yieldingly hold the two portions of the plug together. It will be seen from this structure that the body members, 60 5^a and 6^a are arranged for relative rotation, thus providing what may be called a separable and swivel attachment plug. In some forms of the device, of course, it is desired to have a swivel plug to prevent 65 tangling of the connecting cords.

From what has been described it is thought the nature of my invention will be readily clear to those skilled in the art. Having however thus described one form which my invention may take, what I claim 70 as new and desire to secure by Letters Patent is:

1. A connecting device of the character described comprising two separable body members, one of said body members having 75 means adapted to hold it in a socket, said other body member having two contact terminals both of which are adapted to engage the terminals of said socket, and means for 80 yieldingly locking said body members together, whereby said second aforesaid body member is detachable from said first aforesaid body member when said first aforesaid body member is within a socket.

2. A connecting device of the character 85 described comprising two separable body members, one of said body members being adapted for primary insertion in a socket and having means adapted to hold it in said socket, said other body member having two contact terminals one of which is adapted to directly engage one of the terminals of said socket, and the other one of which is 90 concentrically located with respect to said connecting device, and means for yieldingly 95 locking said body members together, whereby said first aforesaid body member when in position is adapted to receive and retain said second body member in position.

3. A connecting device of the character 100 described comprising two separable body members, one of said body members having means adapted to hold it in a socket, said other body member having two contact terminals one of which is adapted to directly 105 engage one of the terminals of said socket, and the other one of which is concentrically located with respect to said connecting device, and means for yieldingly locking said body members together, said first aforesaid 110 body member having a cut away portion to accommodate the first aforesaid contact terminal.

4. A connecting device of the character described comprising two separable body members, one of said body members having means adapted to hold it in a socket, said other body member having two contact elements both of which are adapted to engage the terminals of said socket, and means for 115 yieldingly and rotatably locking said body members together, whereby said second aforesaid body member is detachable from said first aforesaid body member when said first aforesaid body member is within a 120 socket.

5. A connecting device of the character described comprising two separable body members, one of said body members being adapted for primary insertion in a socket 130

and having means adapted to hold it in said socket, said other body member having two contact terminals one of which is adapted to directly engage one of the terminals of 5 said socket, and the other one of which is concentrically located with respect to said connecting device, and means for yieldingly and rotatably locking said body members together, whereby said first aforesaid body 10 member when in position is adapted to receive and retain said second body member in position.

6. A connecting device of the character described comprising two separable body 15 members, one of said body members having means adapted to hold it in a socket, said other body member having two contact terminals one of which is adapted to directly engage one of the terminals of said socket, 20 and the other one of which is concentrically located with respect to said connecting device, and means for yieldingly and rotatably locking said body members together, said first aforesaid body member having a cut- 25 away portion to accommodate the first aforesaid contact terminal.

7. A connecting device of the character described comprising two separable body 30 members, one of said body members having means adapted to hold it in a socket, said other body member having two contact elements both of which are adapted to engage the terminals of said socket, and means for yieldingly and rotatably locking said body 35 members together, said first aforesaid body member having means to guide the second body member into its contact making position.

8. A connecting device of the character 40 described comprising two separable body members, one of said body members having means adapted to hold it in a socket, said other body member having two contact terminals one of which is adapted to directly engage one of the terminals of said socket, and the other one of which is concentrically located with respect to said connecting device, and means for yieldingly and rotatably locking said body members together, 45 said first aforesaid body member having means to guide the second body member into its contact making position.

9. A connecting device of the character 50 described comprising two separable body members, one of said body members having means adapted to hold it in a socket, said other body member having two contact terminals one of which is adapted to directly engage one of the terminals of said 55 socket, and the other one of which is concentrically located with respect to said connecting device, and means for yieldingly and rotatably locking said body members together, said first aforesaid body member 60 having a cut-away portion to accommodate

the first aforesaid contact terminal, said first aforesaid body member having means to guide the second body member into its contact making position.

10. A connecting device of the character 70 described comprising two separable body members, one of said body members having means adapted to hold it in a socket, said other body member having two yielding contact terminals both of which are adapted 75 to engage the terminals of said socket, and means for yieldingly locking said body members together, whereby said second aforesaid body member is detachable from said first aforesaid body member when said 80 first aforesaid body member is within a socket.

11. A connecting device of the character described comprising two separable body 85 members, one of said body members being adapted for primary insertion in a socket, said other body member having two yielding contact terminals one of which is adapted to directly engage one of the terminals of said socket, and the other one of which is concentrically located with respect to said connecting device, and means for yieldingly locking said body members together, whereby said first aforesaid body 90 member when in position is adapted to receive and retain said second body member in position.

12. A connecting device of the character described comprising two separable body 100 members, one of said body members having means adapted to hold it in a socket, said other body member having two yielding contact terminals one of which is adapted to directly engage one of the terminals of 105 said socket, and the other one of which is concentrically located with respect to said connecting device, and means for yieldingly locking said body members together, said first aforesaid body member having a cut-away portion to accommodate the first 110 aforesaid contact terminal.

13. A connecting device of the character described comprising two separable body 115 members, one of said body members having means adapted to hold it in a socket, said other body member having two yielding contact elements both of which are adapted to engage the terminals of said socket, and means whereby said body members are rotatably and yieldingly held together, whereby said second aforesaid body member is detachable from said first aforesaid body member when said first aforesaid body member is within a socket.

14. A plug of the character described 125 adapted for insertion in a socket, comprising two separable body members, one of said body members being adapted for primary insertion in said socket and having means 130

adapted to hold it therein, means whereby said other body member may be moved into its coöperating position with said first aforesaid body member and held in rotative association therewith when said first aforesaid body member is in position in the socket, said other body member carrying contact elements for establishing circuit conditions with said socket, both of said contact 10 elements directly engaging the conducting portions of said socket.

15. A plug of the character described adapted for insertion in a socket, comprising two separable body members, one of said body members being adapted for primary insertion in said socket and having means adapted to hold it therein, means whereby

said other body member may be moved into its coöperating position with said first aforesaid body member when said first aforesaid body member is in position in the socket, said other body member carrying contact elements for establishing circuit conditions with said socket, both of said contact elements directly engaging the conducting portions of said socket. 20 25

In witness whereof, I hereunto subscribe my name this 21st day of February, A. D. 1916.

DAVID D. GORDON.
